CLAIM

The ornamental design for an electrode, as shown and described.

DESCRIPTION

FIG. 1 is a perspective view of an electrode showing the new design;

FIG. 2 is a front elevation view thereof;

FIG. 3 is a rear view thereof;

FIG. 4 is a top plan view thereof;

FIG. 5 is a bottom plan view thereof;

FIG. 6 is a right elevation view thereof;

FIG. 7 is a left elevation view thereof; and,

FIG. 8 is a perspective view of the electrode in a second position of use wherein an interior portion is shown in a second position of use, the rear surfaces of the interior portion are comprised of unclaimed subject matter.

(Continued)

The broken lines constitute environment and, thus, unclaimed subject matter.
